UNITED STATES PATENT OFFICE

2,076,454

FLOAT SWITCH

Roland Y. Foxwell, Cape Charles, Va.

Application December 11, 1935, Serial No. 53,996

1 Claim. (Cl. 200—84)

This invention relates to a unique structural assemblage which, in a unitary sense, may be referred to briefly as a safety gauge equipped fuel holder or container.

5 The invention has more specific reference to the inverted type oil reservoir or supply means susceptible of being used on oil heating apparatus, and so-called kitchen cooking stoves or ranges.

The preferred embodiment of the invention 10 embodies a regular gallon capacity glass bottle having an especially equipped closing cap formed with a float-controlled switch, said switch-equipped end of the container being adapted to be supported in the oil feeding pan, such as is 15 connected with the burners or other appliances.

Specific novelty is predicated on the one hand on the basin type holder constructed to accommodate special float and switch means, and itself having a special rim formed with an insulated 20 contact ring in order to satisfactorily accomplish the desired results.

Additional novelty resides in particular in a 25 special closing cap of an insulated character, this having a float and switch structure associated therewith as well as a fuel control discharge valve.

Other features and advantages will become more readily apparent from the following description and drawings.

30 In the accompanying drawings wherein like numerals are employed to designate like parts throughout the views:

Figure 1 is a view partly in section and partly in elevation showing the complete assemblage 35 and the manner in which it operates.

Figure 2 is a perspective view of the special switch equipped tank or container valving and closing unit.

Figure 3 is a top plan view of the so-called 40 basin illustrating the audible signal wiring associated therewith.

The purpose of the invention is, obviously, to give an audible signal when the supply of oil is 45 too low for safe stove operation.

45 Calling attention first to Figure 1 it will be observed that the transparent oil tank or container is indicated by the numeral 4 and comprises a gallon type glass jar to contain the oil or other fuel 5. It includes a threaded neck 6 and when the device is in use the jar is inverted 50 as shown in the drawings.

A special closure unit is associated with the neck 6. This comprises a screw cap 7 constructed of insulation material. Connected with 55 this and projecting therefrom is a spring metal

contact arm or finger 8. This has the configuration illustrated better in Figure 1 and the inner end portion thereof extends through an aperture in the cap and into the cap where it terminates in a yieldable contact element or point 9.

The control valve comprises a hollow or tubular stem 10, slidably mounted in a central guide aperture in the cap and having a stop disk 11 at its inner end. There is a somewhat larger presser foot or disk 12 at the opposite outer end of the valve tube. The oil enters the tube through the inlet port 13 and is discharged through the outlet port 14.

Attached to and projecting into the jar from the cap is a metal casing 15 which may be conveniently referred to as a cage or guide for the hollow metal float 16. Incidentally, the oil from the main chamber enters the float casing 15 by way of suitable apertures 17. The float has an elevated bottom 18 defining an annular circuit make and break rim 19. This rim is disposed directly above and is intended to come down into engagement with the spring contact element 9 as shown in dotted lines in Figure 1. This happens when the level of the oil goes down sufficiently low to permit the float to drop down to circuit closing position. At the same time the elevated bottom 18 rests on the metal disk or head 11 and completes the circuit in a manner to be hereinafter described.

The basin or pan is denoted by the numeral 19 and includes an outlet 20 leading to the feed or supply pipe 21 which is in turn connected with the stove (not shown). The rim of the basin is indicated at 22 and is fashioned to serve as a seat or rest for the inverted glass tank 4. On its upper side the rim carries a metal contact annulus or ring 23 and interposed between this and the rim is an insulator 24. As shown in Figure 1 the free end of the contact 8 extends out and is in electrical engagement with the annulus 23 when the device is set up for operation. It is yet to be mentioned that the cut-off valve is of a spring-pressed type, that is it includes a suitable coiled spring 25 which normally keeps the valve closed, that is pulls the valve stem through the cap 7 to normally close the inlet ports 13 in an obvious manner.

In Figure 3 the numeral 26 designates the battery, 27 indicates a bell, 28 indicates a wire extending from the battery to the annulus or ring 23, 29 indicates the bell wire which is grounded on the pipe 21. It is evident therefore, that when the inverted glass tank is placed in the bowl or basin the valve is pushed open to allow the oil to 55

flow from the jar or tank through the pipe 21 as needed. This also places the structure in readiness to sound the alarm when the level of the oil is abnormally low. The oil enters through the 5 top opening 17 in the casing 15 as well as through the bottom slot 30. As the float 16 goes down with the fall of the oil column it is evident that the rim 19 comes into engagement with the spring-contact element 9. Almost simultaneously 10 the elevated bottom 18 comes into contact with the head or disk 11 and this closes the circuit and sounds the alarm as is obvious.

The novelty as set forth in the adjoined claim is primarily structural and is directed to the 15 structure collectively and partly.

It is thought that persons skilled in the art to which the invention relates will be able to obtain a clear understanding of the invention after considering the description in connection with the 20 drawings. Therefore, a more lengthy description is regarded as unnecessary.

Minor changes in shape, size and the arrangement of details coming within the field of invention claimed may be resorted to in actual 25 practice, if desired.

I claim:

An attachment for jar necks of the class described comprising a screw cap constructed of electrical insulating material, a tubular spring-pressed normally closed valve in the bottom portion of said cap, said valve being constructed of electrical conducting material and in its open position having its inner end projecting into said cap, a yieldable electrical contact element in said cap, an electrical conducting member secured to 10 said contact element and extending through said cap, a float guide secured to said cap enclosing said electrical contact element and having an aperture in the upper portion thereof, said guide enclosing the inner portion of said valve, a float 15 mounted in said guide constructed of electrical conducting material, a bottom constructed of electrical conducting material in said float spaced from the rim thereof, the rim of said float and the bottom thereof being simultaneously cooperable 20 respectively with the electrical contacting element and the projected end of said valve in said rim for effecting an electrical conducting path therebetween.

ROLAND Y. FOXWELL. 25
